VENTILATING BUILDING STRUCTURE

Moses G. Lee, Cuthbert, Ga.

Application September 19, 1938, Serial No. 230,712

4 Claims. (Cl. 98—42)

The invention relates to a ventilating building structure and more especially to an air conditioning construction for buildings or the like.

The primary object of the invention is the provision of a structure of this character, wherein in the roof to a building is so designed and made up that it enables air conditioning of the building during summer months and also enables proper ventilation to such edifice, the structure being novel in its entirety.

Another object of the invention is the provision of a structure of this character, wherein the eaves about the roof of a building are so constructed that the same can be opened in that a boxing is disposed throughout the eaves or along the side walls of the building and this boxing is provided with gates functioning as valves so that heat or climatic conditions within the building can be properly conditioned and ventilation is assured.

A further object of the invention is the provision of a structure of this character, which is thoroughly reliable and efficient in operation, enabling the area next to the roof of the building to be cooled in that outside air can circulate therethrough and warm air discharge therefrom and also inexpensive to manufacture and install.

With these and other objects in view, the invention consists in the features of construction, combination and arrangement of parts as will be hereinafter more fully described, illustrated in the accompanying drawings, which disclose the preferred and modified forms of embodiment of the invention and pointed out in the claims hereunto appended.

In the accompanying drawings:

Figure 1 is a fragmentary vertical sectional view through a building showing the structure constructed in accordance with the invention.

Figure 2 is an enlarged fragmentary transverse sectional view through the ridge of the roof.

Figure 3 is a sectional view on the line 3—3 of Figure 1 looking in the direction of the arrows.

Figure 4 is a sectional view on the line 4—4 of Figure 1 looking in the direction of the arrows.

Figure 5 is a fragmentary sectional view taken on the line 5—5 of Figure 1 looking in the direction of the arrows.

Figure 6 is a view similar to Figure 3 showing a modified form of structure.

Figure 7 is a fragmentary perspective view in detail of the ridge beam involved in the modification shown in Figure 6.

Figure 8 is a fragmentary vertical transverse

sectional view through a building showing a modification at the eaves of the roof.

Similar reference characters indicate corresponding parts throughout the several views in the drawings.

Referring to the drawings in detail, particularly Figures 1 to 5, inclusive, A designates generally a portion of a building and B a ridged roof thereto. This roof B involves the reversely angled rafters 10 supporting the roof boards or the like 11 while 12 is the roof covering of any selected material. These rafters 10 extend to a ridge formation 13 which includes a pair of superposed ridge rails or beams 14 and 15, respectively, which intermediate thereof fit with a 16 divider strip 16 having vertically arranged holes 17 arranged in rows and spaced from each other at opposite sides of the ridge rails or beams 14 and 15 while fitting the longer side edges of the strip 16 are flashings 18 of metal, these being fastened to the roof boards 11 in any desirable manner and are at opposite sides of the ridge. The roof boards 11 terminate short with respect to the ridge rails or beams 18, thereby effecting vent passages 19 below the perforations 17 in the strip 16.

Crowning the ridge rail or beam 14 uppermost of the ridge is a reticulated crowning screen 20 being coextensive with the ridge of the roof B. Overlying the screen 20 is a ridge roll 21, being flared outwardly at opposite longer side edges so that ventilation is assured through the screen 20 in the ridge of the roof.

The walling 22 to the building A terminates at opposite sides thereof removed from the roof boards 11 so that a space equal to or substantially equal to the rafters 10 in their depth is provided at the eaves of the roof B and this space is effective as windows 23 beneath the roof following the eaves. The windows 23 are covered with reticulated screens 24. These windows are between the rafters 10 while slidably fitted, as at 25, to the rafters are shutters 26, which regulate the extent of the windows 23 in that the opening extent thereof can be regulated through adjustment of the said shutters 26, these being made fast in adjusted position by suitable fasteners 27. Thus ventilation to the interior of the building at the windows 23 and at the ridge of the roof B can be had with the result that air conditioning interiorly of the building is accomplished.

In Figures 6, 7 and 8 of the drawings there is shown a slight modification of the structure wherein the ridge beams or rails 28 and 29 are

separated from each other and in lieu of the strips 16 cross pieces are interposed between said rails or beams, these being spaced from each other the required distance. Otherwise the ridge 5 formation is similar to that hereinbefore described with respect to the use of the rails or beams 28 and 29 and pieces 30, respectively.

In Figure 8 of the drawings at the eaves and in association with the windows 31 similar to the 10 windows 23 is a boxing 32, the lowermost portion of which has provided therein a drop gate or door 33, which, when closed, prevents ventilation at the windows 31, and when opened, ventilation can be had through such windows.

15 It is desirable that in the summer period the ridge formation and the windows at the eaves of the edifice afford maximum ventilation for air conditioning interiorly of the building while in the winter period, the windows at the eaves can be closed 20 to avoid chilling the interior of the building from outside temperature while the warm air may discharge to the atmosphere through the ridge formation and proper ventilation is assured within the building to a maximum degree.

25 What is claimed is:

1. A structure of the kind described comprising a roof having a ridge, a ridge rail built at the ridge and rising vertically above the same, said ridge being provided with openings at opposite 30 sides of the ridge rail, laterals projecting beyond opposite sides of said rail above the openings in the ridge and below the uppermost edge of said rail, a reticulated crown saddled over the said rail and having fastening with the said laterals, 35 flashings rising from the roof at opposite sides of the rail and joined with the crown at the laterals, and a ridge roll overhanging said crown and outwardly spread with relation to the same and the flashings.

40 2. A structure of the kind described comprising a roof having a ridge, a ridge rail built at the ridge and rising vertically above the same, said ridge being provided with openings at opposite sides of the ridge rail, laterals projecting beyond 45 opposite sides of said rail above the openings in

the ridge and below the uppermost edge of said rail, a reticulated crown saddled over the said rail and having fastening with the said laterals, flashings rising from the roof at opposite sides of the rail and joined with the crown at the laterals, 5 and a ridge roll overhanging said crown and outwardly spread with relation to the same and the flashings, the said laterals being constructed for ventilation between the flashings and the said reticulated crown.

10 3. A structure of the kind described comprising a roof having a ridge, a ridge rail built at the ridge and rising vertically above the same, said ridge being provided with openings at opposite sides of the ridge rail, laterals projecting beyond 15 opposite sides of said rail above the openings in the ridge and below the uppermost edge of said rail, a reticulated crown saddled over the said rail and having fastening with the said laterals, flashings rising from the roof at opposite sides 20 of the rail and joined with the crown at the laterals, a ridge roll overhanging said crown and outwardly spread with relation to the same and the flashings, the said laterals being constructed for ventilation between the flashings and the said 25 reticulated crown, and vent means built at the edges of said roof.

4. A structure of the kind described comprising a roof having a ridge, a ridge rail built at the ridge and rising vertically above the same, said 30 ridge being provided with openings at opposite sides of the ridge rail, laterals projecting beyond opposite sides of said rail above the openings in the ridge and below the uppermost edge of said rail, a reticulated crown saddled over the said 35 rail and having fastening with the said laterals, flashings rising from the roof at opposite sides of the rail and joined with the crown at the laterals, a ridge roll overhanging said crown and outwardly spread with relation to the same and 40 the flashings, the said laterals being constructed for ventilation between the flashings and the said reticulated crown, vent means built at the edges of said roof, and controls for said vent means.
